FIREARM.

1,178,747.

Specification of Letters Patent. Patented Apr. 11, 1916.

Application filed December 13, 1913. Serial No. 806,483.

To all whom it may concern:

Be it known that I, CHARLES A. NELSON, a citizen of the United States, residing at Utica, in the county of Oneida and State of 5 New York, have invented certain new and useful Improvements in Firearms, of which the following is a specification.

The object of this invention is to provide a gun having many of the desirable features 10 of the gun set forth in the Savage Patent No. 839517 but possessing, in addition to improvements which increase the simplicity of construction, durability, stability, safety and general efficiency of a gun of that kind, 15 the quality of being semi-automatic, that is, adapted by the back-pressure of the charge on explosion, to withdraw and eject the empty shell, breech a fresh cartridge and cock the firing mechanism.

20 In the accompanying drawings, wherein the invention is fully illustrated, Figure 1 is a side elevation of the improved gun; Figs. 2 and 3 are inside elevations of the stock and barrel sections, respectively, of 25 the receiver and of the parts of the mechanism respectively associated with them; Fig. 4 shows the receiver-including part of the gun partly in right side elevation and partly in section; Fig. 5 shows said part of the gun 30 partly in left side elevation and partly in section; Fig. 6 shows the forearm-including part of the gun partly in side elevation and partly in section; Fig. 7 is a plan of portions of the receiver, action slide and the means 35 for returning the action slide to its normal position; Fig. 8 is a plan of the rear part of the forearm; Fig. 9 is a sectional view on line x—x of Fig. 2, looking forward; Fig. 10 is a perspective view of the cartridge 40 stop or abutment and breech-bolt; Fig. 11 shows the magazine platform blocking the advance of the breech-bolt after effecting ejection of the shell c² the last cartridge in the magazine; and, Fig. 12 is a detail of 45 the ejector.

The receiver or frame, substantially similar to that in the patent to Savage above-mentioned, comprises a stock section a' and a barrel section a'' which lie face to face 50 when assembled, being interlocked by the mortise and tenon connections b and c (Figs. 2, 3, and 7) and held together by the single thumb-screw d entered through the section a'' into section a'.

55 f is the stock and g the barrel.

h is the magazine, of the box type, suitably held in the receiver by the latch i substantially the same as in the said Savage patent.

The action-slide is a bar j guided in a straight slot k in the inner face of receiver-section a'' and projecting through the front wall thereof; its rear end has a handle for manually retracting the action slide, said handle consisting of a knob l and a pivoted notched part or latch m of the action slide which carries the knob and moves in a slot n (Fig. 1) in receiver-section a'' and has its hook m' engageable with a notch m'' (Fig. 3) at the rear end of said slot and on the inside to hold back the action slide when depressed against a spring o (Figs. 5 and 7). The forward end of said action-slide carries the lateral collar p traversed by the pin q. Directly under the barrel is a tubular spring-case r penetrating and guiding said collar and having longitudinal slots s in which pin q plays, the rear end of said spring-case being received by the front wall of receiver-section a'' and the forward end supported by the stirrup t having a dove-tailed base u entered into a lateral similar shaped slot v cut in the under side of the barrel. A spiral spring w, housed in the case and interposed between the pin q and a suitable abutment x at the rear end of the case, presses the action slide forward. The forearm y, suitable hollowed out to fit the under side of the barrel and house the spring-case and stirrup t and afford the necessary clearance to the action-slide latch m, is secured in place in a way calculated to produce a simple, stout and readily assembled construction, thus: It has its rearward end formed as a broad tenon z fitting a mortise 2 formed in the front wall of the receiver, the vertical surfaces of said tenon and mortise being curved in plan (Figs. 7 and 8); screw 3 enters the forearm and receiver at said joint, while a screw 4 is passed through the forearm, stirrup t and case r, being tapped into the stirrup and having a reduced end 4' which enters the barrel and so locks the stirrup against lateral movement (Fig. 6). In this way the forearm is secured to the barrel and receiver so that the construction is at once simple and adapted to facilitate assembling, besides the joint between the forearm and receiver is such as to have exceeding strength, to re- 100 105 110

quire but a single screw (3) to preserve it, and to prevent the wood of the forearm against splitting or chipping at the joint. The action slide has its rear end the spaced lateral lugs 5 and 6.

The breech-bolt 7 is generally like the breech-bolt described in the said Savage patent, being guided by the side walls of the receiver, having a cheek-piece or wall 8 on one side resting on the action-slide (which, being thicker than slot 7 is deep, projects therefrom) and abutted above by the top wall of the receiver; it has a firing pin 9, an extractor 10 coactive with projections 10' to hold the cartridge and, on the side thereof relatively opposite to said cheek-piece, a longitudinal slot 11, and is otherwise formed and operates the same as in the said Savage patent (excepting that it lacks the means for blocking it against recoil), the slot 11 being adapted to receive the acting end of the ejector 12 which springs inwardly to throw the extracted shell out of the ejection aperture 13 in the receiver when the receding breech-bolt, by its extractor, clears the shell from the barrel. The breech-bolt has a downwardly depending tail 7' fitting between the lugs 5 and 6 on the action-slide.

The ejector 12 is a lever having its fulcrum formed by a hook 12' (Fig. 12) engaging in an annular channel 12'' formed in the inner side of the head of a screw 14; the lever and screw-head are received in a communicating slot 12''' and countersink 13' and a spring 15 in the slot presses the free or acting end of the lever outwardly, tending to hold it to the limit of outward movement thereof which is afforded by the contact of the inner end 12'''' of the lever against the bottom of the countersink.

The top wall of the receiver has a recess or chamber 16 formed immediately back of the barrel-breech, the object of which is to afford ample blow-back relief for the escaping products of combustion and gases on firing, which would otherwise be unduly confined in the relatively limited space formed by the top and sides of the receiver chamber, the underlying magazine and its contents, the barrel-breech and front end of the breech-bolt and so interfere more or less with the free action of the parts and sooner or later foul the piece. For checking the fresh cartridge rising from the magazine at a position in line with and guiding it into the barrel breech I employ the stop 17 shown in Figs. 3, 4, 5, 10 and 11 which is a slender elastic metallic strip having parallel upstanding cheeks 18 secured in a slot 19 in the top wall of the receiver by a transverse pin 20 and a spoon-shaped free end 21, its said spoon-shaped end traversing chamber 16 and being normally slightly below the level of the top of the bore so that on yield-

ing to the upward pressure of the magazine spring it will occupy such a position relatively to the bore as then to perform its function properly as a guide to the cartridge in breeching the same.

In order to insure the breech-bolt (which is the only freely removable element of the mechanism) remaining properly assembled with the receiver section a' on taking down I provide the member 17 with a lug 22 which is received by the groove 22' at the top of the breech-bolt.

The hammer 23, having the head 24 to impinge against the firing pin and the cam-face 25 to receive the wiping action of the lug 6 on the action-slide, in cocking the hammer, and the spring-pressed thrust-bar 26 for the hammer are substantially the same as in said Savage patent.

The trigger 27, in the form of a rearwardly open housing, is fulcrumed at its mid-upper portion on the pin 28, being protected by the usual guard 29 affording a backing for the magazine. On the pin 28 is fulcrumed the sear 30 having the forwardly, rearwardly and long downwardly projecting arms 30', 30'' and 30''''. On a pin 31 in the trigger is fulcrumed the sear-trip 32 having the forwardly curved upper arm 32' and the downwardly projecting arm 32'' and on its upper arm the shoulder 32''' to engage under the end of arm 30' of the sear. A spring 33 interposed between the lower arms of the sear and sear-trip tends to turn them in opposite directions on their fulcra. The hammer has a cocking notch 23' to be engaged by the arm 30' of the sear, and, back of said notch, a cam-surface 23'' to be engaged by the arm 32' of the sear-trip, and, forward of said notch, the concentric surface 23''''. A plate spring 34 pressing downwardly on the locking-bar 35, suitably guided in a slot in the thrust-bar 26 and stepped on a cross-pin 36 in the rearwardly projecting arm of the trigger, through the thrust-bar forces the trigger forward, normally holding the upper edge of its front wall 27' in contact with the sear arm 30', which rests against the hammer; the locking-bar (movable upwardly under the influence of the trigger and also forward and backward pivotally on the cross-pin 36) is received by a slot 37 in the receiver and is moved forward or backward to bring one of its stepped shoulders 35', 35'' under the shoulder 35''' at the rear of said slot by the usual slide 38 which is penetrated by a stud 39 on the locking-bar. The action of these parts is as follows: The parts being in the cocked position (Fig. 4) rearward movement of the trigger causes the sear-trip, whose fulcrum is in the trigger, to trip the sear (fulcrumed on the stationary pin 28) so that the hammer falls; spring 33 meanwhile holds both the sear and sear-trip against the

locking-bar (movable upwardly under the influence of the trigger and also forward and backward pivotally on the cross-pin 36) is received by a slot 37 in the receiver and is moved forward or backward to bring one of its stepped shoulders 35', 35'' under the shoulder 35''' at the rear of said slot by the usual slide 38 which is penetrated by a stud 39 on the locking-bar. The action of these parts is as follows: The parts being in the cocked position (Fig. 4) rearward movement of the trigger causes the sear-trip, whose fulcrum is in the trigger, to trip the sear (fulcrumed on the stationary pin 28) so that the hammer falls; spring 33 meanwhile holds both the sear and sear-trip against the

hammer and as the hammer falls its cam 23" wipes the sear trip out of engagement at its shoulder 32" with the sear arm 30", while the sear arm 30' wipes over the concentric 5 surface 23'" of the hammer. If (there being no charge in the gun) the hammer remains down, as in Fig. 9, the trigger will at this time be held from any lost motion, being retained against the sear arm 30', which 10 itself abuts the hammer, by the shoulder 35' of locking bar 35 engaging shoulder 35"". If, recoil occurring from an exploded charge, the hammer is thrown back, the sear, being clear of the sear trip and hence of the 15 trigger, is free to act independently of the trigger to engage the hammer notch 23' and cock the hammer although (as will usually be the case) the operator's finger has not allowed the full return of the trigger which. 20 when it does move forward, brings the sear trip opposite the low part of cam 23" whereby it will be allowed to again assume dogging relation to the sear. In the cocked position of the parts the trigger may be 25 locked by moving the slide 38 rearward so as to bring shoulder 35" on the locking bar under the shoulder 35"".

The stud 39 is sufficiently longer than the slide is thick so that with the trigger forward (hammer cocked) its extremity is approximately flush with the top of the slide: with the trigger back (hammer down) the stud projects, indicating to the operator's thumb the uncocked condition of the piece.

35 The magazine *h* has the usual platform 40 to elevate the cartridges contained therein and to block the breeching movement of the breech-bolt upon the magazine becoming empty (Fig. 11), the same as in the patent 40 to Savage No. 885868.

Operation: The operation will be apparent to those familiar with this class of guns. To breech the first cartridge in the magazine the action slide *j* is retracted and 45 then allowed to return under pressure of spring *w*, forcing the cartridge (which has been meanwhile pressed by the platform 40 into the grip of the devices 10 10' on the breech-bolt) into the breech. Upon the gun 50 being now fired the recoil of the breech-bolt, through the action-slide, throws back the hammer which is immediately cocked, while the spent shell is extracted and ejected and, on the return of the action-slide and breech- 55 bolt to their normal positions, a fresh cartridge breeched. When the last cartridge has been exploded the breech-bolt and action-slide will be locked back by the platform 40 rising and blocking the return of the breech-bolt as illustrated in Fig. 11, thus indicating that the piece is empty. To now recharge the piece, the action-slide is locked back by the latch *m*, the empty magazine withdrawn and a loaded one substituted, 60 whereupon, the latch being released, the

breech-bolt will in advancing pick off the uppermost cartridge and breech it in the usual way, ready for firing.

Having thus fully described my invention, what I claim as new and desire to secure by Letters Patent is:—

1. In combination, the barrel, a longitudinally movable breech-bolt, means, including a substantially longitudinally and vertically divided receiver, in which the breech-bolt is guided against lateral displacement, said means affording in one of the sections of the divided receiver support for one of the upper and lower sides of the breech-bolt and a yielding retaining member 75 engaging the breech-bolt at a relatively opposite side thereof and separably interlocking the same with said section, substantially as described.

2. In combination, the barrel, a longitudinally movable breech-bolt, means, including a substantially longitudinally and vertically divided receiver, in which the breech-bolt is guided against lateral displacement, said means affording in one of the sections of the divided receiver an underlying support for the breech-bolt, and a yielding retaining member engaging the breech-bolt at an upper side thereof and separably interlocking the same with said 90 section, substantially as described.

3. In combination, the barrel, the receiver, the breech-bolt, the magazine discharging into the receiver between the barrel-breech and the rearward position of the breech-bolt, firing means, said receiver including two separable sections one of which carries the breech-bolt, and a cartridge stop arranged in said section opposite the magazine and separably interlocking said breech-bolt 100 with said section, substantially as described.

4. In combination, the barrel, the receiver, the breech-bolt, said receiver including two separable sections one of which carries the breech-bolt, and an elongated yielding member secured at one end in said receiver-section and having its other end free and separably interlocking the breech-bolt with 110 said section, substantially as described.

5. In combination, the barrel, the receiver, the breech-bolt, firing means, said receiver including two separable sections one of which carries the breech-bolt, and a cartridge guide projecting toward the barrel and arranged in said section and separably interlocking said breech-bolt with said section, 120 substantially as described.

6. In combination, the barrel, the receiver, the breech-bolt, and a cartridge-engaged member having one end free and yielding 125 and the other end provided with parallel cheeks, said receiver being interiorly recessed and receiving said cheeks, and a securing device extending through the receiver and said cheeks, substantially as described. 130

7. In combination, the receiver having an ejection opening in one wall thereof, a headed screw tapped from the inside into the opposite wall of the receiver, and a spring-pressed ejector lever having one end overlapped by the screw head, the head of said screw having on the inside thereof an annular fulcrum for said end of the ejector lever, substantially as described.
- 10 8. In combination, the receiver having an ejection opening in one wall thereof, a headed screw tapped from the inside into the opposite wall of the receiver, the head of said screw being annularly grooved on the inner side thereof, and a spring pressed ejector-lever having one end overlapped by the screw head and engaged in the groove thereof, substantially as described.
- 15 9. In combination, the receiver having an ejection opening in one wall thereof, a headed screw tapped from the inside into the opposite wall of the receiver, and a spring-pressed ejector lever having one end overlapped by the screw head, the head of said screw affording an annular fulcrum for said lever and coacting with the latter wall of the receiver to limit the movement of said lever, substantially as described.
- 20 10. In combination, the receiver, the barrel, the breech-bolt movable toward and from the barrel, the action-slide coupled with the breech-bolt and movable longitudinally of the barrel, means normally acting to force forward the action-slide, and the firing mechanism, the action-slide having on one side a handle pivoted on a horizontal axis for manually retracting the action-slide and the receiver, a notch engageable by said handle in the retracted position of the action-slide to hold back the latter.
- 25 11. In combination, the receiver, the barrel, the breech-bolt movable toward and from the barrel, the firing mechanism including a hammer backwardly moved to the cocked position by the breech-bolt and underlying the latter in the backward position of the hammer, and the action-slide movable back and forth beside the hammer and having on the side adjoining the latter spaced lugs, said breech-bolt having a depending tail in a plane beside the plane of movement of the hammer and engaged between said lugs, substantially as described.
- 30 12. In combination, the receiver, the barrel, and the forearm under the barrel, the front of the receiver and the rear end of the forearm having surfaces extending straight upwardly from their respective under surfaces and formed the former concave and the latter convex and abutting and closely fitting each other, whereby to produce a mortise and tenon joint between the forearm and receiver, substantially as described.
- 35 13. In combination, the receiver, the barrel, the hollow forearm under the barrel, means for feeding the cartridges to the barrel and exploding the same including an elongated member housed in the forearm under the barrel, and a common means for securing the forearm and said member to the barrel, substantially as described.
- 40 14. In combination, the receiver, the barrel, the forearm under the barrel, the front of the receiver and the rear end of the forearm having surfaces extending straight upwardly from their respective under surfaces and formed the former concave and the latter convex and abutting and closely fitting each other, whereby to produce a mortise and tenon joint between the forearm and receiver, and a screw extending upwardly through the tenon into the receiver.
- 45 15. In combination, the receiver, the barrel, means for feeding the cartridges to the barrel and exploding the same including an elongated tubular spring case, a stirrup supporting the case and having a sliding interlocking connection with the barrel, and a screw penetrating the stirrup and the case and projecting into the barrel, substantially as described.
- 50 16. In combination, the receiver, the barrel, the hollow forearm under the barrel, means for feeding the cartridges to the barrel and exploding the same including an elongated member housed in the forearm under the barrel, a stirrup carrying said member and having a dove tailed interlocking engagement with the barrel, and a screw penetrating said forearm and the stirrup and extending into the barrel, substantially as described.

In testimony whereof I affix my signature in presence of two witnesses.

CHARLES A. NELSON.
